UNITED STATES PATENT OFFICE.

ARTHUR S. COWAN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM.

No. 814,000.

Specification of Letters Patent.

Patented Feb. 27, 1906.

Application filed December 28, 1903. Serial No. 186,798.

To all whom it may concern:

Be it known that I, ARTHUR S. COWAN, a citizen of the United States, residing at Worcester, in the county of Worcester and State of Massachusetts, have invented an Improvement in Looms, of which the following description, in connection with the accompanying drawings, is a specification, like letters and figures on the drawings representing like parts.

This invention has for its object the production of a novel loom for weaving fabrics in which short or separate lengths of weft are laid in sheds formed in warp-threads, the loom herein to be described also having the capacity of inserting into sheds in the warp following those in which the short wefts are inserted a weft taken from a cop or bobbin and hereinafter designated as a "continuous" weft as contradistinguished from a short weft. The short wefts will preferably be of hair or some such material that will give stiffness to the fabric between its selvages and will aid in maintaining the warps separated as determined by the weave of the fabric, it being understood that the warps may be manipulated by shed-forming mechanism in the formation of the sheds as they are commonly manipulated in weaving plain or twill cloth or in weaving leno or cross or any fancy weaving. The manipulation of the warps depends on the shed-forming mechanism, and in connection with my invention, to be hereinafter more fully described, I may use any known form of shed-forming mechanism, that depending on the weave or character of the cloth to be woven.

Prior to this invention hair-wefts in short lengths have commonly been engaged at their leading ends and drawn into the shed by means of nippers moving transversely of the warps and traversing the shed, the short wefts of hair or whatever material being taken one at a time from a bunch at the loom end. I have devised an entirely new system and means whereby fabrics containing short wefts in whole or part may be woven, and, if desired, a continuous weft may be inserted at intervals in any sheds omitting the short wefts.

In accordance with my invention I employ a shuttle for carrying a plurality of wefts which are selected singly by suitable short-

weft-selecting means, each selected weft being engaged by a weft-holder. The weft-holder after taking the selected weft from the selecting means is moved toward and is stopped outside one selvage, while the shuttle carrying the remaining portion of the selected weft is moved through the shed into the opposite box, the shuttle in traversing the shed paying out the selected weft, a part of which is yet engaged by the weft-holder, the said shuttle leaving the short weft in the shed to be beat into the fell in usual manner. Further, besides employing a shuttle as the means for holding a plurality of short wefts and for laying said short wefts in the shed by moving the shuttle across the warps I have provided means whereby said shuttle is carried in a shuttle-box, so that the short-weft-carrying shuttle-box, with its shuttle, may be put into operative or inoperative position with relation to the race of the lay, as it is desired that said shuttle shall be operated to lay a short weft or its operation be suspended for any desired number of picks, that depending on usual shuttle-box pattern mechanism. The shuttle-box illustrated has a cell (shown as located below the shuttle-box cell) for controlling the short-weft-containing shuttle, and when the cell of the shuttle-box containing the short-weft-containing shuttle is in its inoperative position the other cell of the shuttle-box containing a shuttle for supplying a so-called "continuous" weft occupies its operative position with relation to the race of the lay. The shuttle-box cell containing the shuttle carrying and presenting the short wefts has coacting therewith weft-selecting means to be described. It will be understood that the loom may have like shuttle-boxes and weft-selecting means at its opposite ends. The short wefts are usually of a length a little in excess of the width from selvage to selvage of the fabric to be woven, and, as will be understood, one end of the short weft is held outside one selvage while the shuttle containing the short weft is being moved through the shed, the leading end of the short weft in the shuttle being delivered therefrom substantially as the shuttle enters the opposite box, and to prevent any accidental curling or undue bending of the short weft that might result in the formation of loops therein when the

reed meets the short weft to beat it into the fell I have provided what I shall hereinafter designate as "short-weft-controlling" means, said means, as herein illustrated, being more or less in number of the warp-threads.

It is customary in looms for weaving perfect goods to provide devices acting to control the stopping of the loom automatically whenever the weft is exhausted or broken, and one part of the loom being stopped all parts are stopped. In the novel loom herein to be described, wherein short wefts are used, the absence of a short weft effects only the immediate stopping, through the feeler cooperating with the lay, of but a part of the loom—viz., the pattern mechanism for controlling both the shed-forming and the shuttle-box-moving mechanisms—and at this time the knives and hooked jacks of the shed-forming mechanism may move and continue to hold open the same shed, the short-weft-selecting means and the means for moving the short-weft-carrying shuttle continuing to run after said pattern-surfaces have been stopped, so that said weft-selecting means, in case a short weft should not be selected when the nippers were first closed, will continue to operate throughout the time allotted therefor in the cycle of operations of the loom, and if the short-weft-selecting means selects a short weft in the allotted time said pattern-surfaces will immediately start again automatically, and the short weft will enter the then open shed—the same shed that said weft should have entered if the selecting means had operated in its proper time. Should the continuous weft be exhausted or broken, the action of the mechanism will be suspended in like manner until the continuous weft has been supplied in usual manner, and at such time the entire loom may be stopped in any usual manner by disconnecting the shaft of the loom, that is driven by power, either the crank-shaft or the cam-shaft, from its primary moving means.

Figure 1 is an elevation looking at the front of a loom at the left-hand end thereof, said loom containing some of the features of my invention, the shuttle-box rod, part of its actuating-chain, and means for moving the picker-stick B⁸ being omitted to avoid complication of the drawing. Fig. 2 is a left-hand end elevation of the loom shown in Fig. 1. Fig. 3 is a partial section of the loom shown in Fig. 1, together with part of the means for moving the shed-forming mechanism and pattern-cylinder and the feeler of the weft stop-motion and part of the take-up. Fig. 4 is an enlarged view of part of the apparatus shown in Fig. 1, the outer guides for the shuttle-boxes, the standard E⁴, and the guide-rod for the weft-holder being broken out, the weft-holder-opening means being omitted, said figure showing the short-weft-selecting means and operating devices there-

for more in detail on a larger scale, the weft-holder being shown as engaging a short weft. Fig. 5 is a plan view of the parts shown in Fig. 4 directly below it looking at Fig. 4 in the direction of the arrow C, but with the parts in the position Fig. 1. Fig. 6 is a plan view of the parts of Fig. 4 directly below it, said figure showing the weft-holder as having been started on its return stroke. Fig. 6^a is a detail showing the weft-holder in its position for holding the short weft near the selvage while the short-weft shuttle completes its movement, this figure showing the parts of Fig. 6 in the position occupied by them just before the weft-holder starts on its return stroke. Fig. 7 shows in elevation the selecting means of Fig. 4, the weft-holder being in a position to engage and hold the short weft selected from the mass carried by the shuttle and next to be laid in the shed. Fig. 8 shows part of the short-weft-selecting means illustrated in Fig. 7, the nippers of the selecting means being shown as having entered the shuttle preparatory to grasping the short weft and as being held open, the shaft D⁷ being rotated, it will be supposed. Fig. 9 is a plan view of a shuttle without the short wefts. Fig. 10 is a section in the line x, Fig. 9, showing the shuttle with a plurality of short wefts laid therein. Fig. 11 is a section of the loom from front to rear, chiefly to show one form of short-weft-controlling means, the means illustrated being adapted to act through the warps that they may act frictionally on the short weft as the latter is laid in the shed. Fig. 12 is a view looking at Fig. 11 in the direction of the arrow 3. Fig. 13 is a detail showing one form of shed-forming mechanism that may be used. Fig. 14 is a detail of the shed-forming pattern-surface and means for rotating the same. Figs. 15 and 16 are details in plan view of the lever moved by the weft stop-motion, showing the clutch, to be described, closed and open. Fig. 17 shows part of the loom represented in Fig. 1 with the shuttle-box rod, part of its actuating-chain, and picker-actuating mechanism. Fig. 18 is a left-hand side elevation of the parts shown in Fig. 17.

Referring to the drawings, A represents part of a loom-frame having erected upon it a stand A' for supporting the arches of the loom, portions of said stand also supporting the head A², (see Fig. 13,) in which is moved the usual knife-bars 14, actuated by an elbow-lever A⁵, common to any dobby-head—as, for instance, in United States Patent No. 388,318, dated August 21, 1888. The loom-frame has a crank-shaft A⁶, that may be driven in any usual manner, the cranks of which are embraced by connecting-rods A⁷, connected with the lay A⁸, pivoted at its lower end in usual manner and having a reed A⁹. The loom-frame also has a cam-shaft A¹⁰, that is driven from the crank-shaft through gears, (shown by dotted lines, Fig. 13^a)

2.) the cam-shaft revolving once while the crank-shaft revolves twice. Part of the warp $w w'$, taken from the warp-beam B, is led over a whip-roll B' and a roller B², and 5 thence in any usual manner, according to the weave of the fabric, through the harnesses, as represented in Fig. 11, thence between the dents of the reed and over the roll B³, sustained in front of the breast-beam B⁴, the 10 fabric being led thence to any usual take-up roll.

The parts so far referred to by letter are and may be common to usual power-loom. The lay has usual guideways to sustain the 15 ends 2 of a shuttle-box B⁵, containing two cells, one above the other. The upper cell contains the novel shuttle B⁶, herein to be described and best illustrated in Figs. 9 and 10, said shuttle carrying a plurality of short 20 wefts a, arranged in a bunch, the shuttle shown in Fig. 9 and representing my invention in one good form having a short-weft-receiving space in which may be laid the bunch of short wefts, the wefts being folded back- 25 wardly, one end of the bunch being cut even and substantially abutting, as shown, a partition a' of the shuttle. The shuttle has a short-weft-tension device a³, (shown as a lever pivoted at a².) the short arm of which is 30 acted upon by a spring a⁴, said spring serving to produce pressure upon the short wefts, forcing the same with a gentle pressure against the abutment a⁵. This lever a³ also yields somewhat as the nippers of the short- 35 weft-selecting means to be described are closed to grasp a short weft. The cell of the undermost shuttle-box of the pair, as herein shown, is adapted to receive a shuttle B⁷, (see Fig. 7,) that may be supplied with a cop or 40 bobbin containing wound filling, said shuttle presenting the continuous filling herein referred to.

Figs. 17 and 18 show the shuttle-boxes B⁶, the box-rod B⁶⁰, the spring B⁶¹, and the chain 45 B⁶², extended over sheaves B⁷² and B⁷³, said parts constituting a portion of usual means for shifting the shuttle-boxes on the lay that either the shuttle containing the short weft or the shuttle containing the continuous weft 50 may be placed at the level of the race of the lay to be moved through a shed in the warps. Further illustration of such mechanism would only tend to complicate the drawings, and it will be understood that I may employ 55 any usual drop-box-shifting mechanism common to Crompton or Knowles or other looms, the position of the shuttle-boxes being controlled automatically by a moving chain B⁶², common to the loom referred to, the time of 60 movement of said chain being determined by indication carried by the usual shuttle-box means and not necessary to be herein illustrated.

The shuttle B⁶, containing the short wefts, 65 and the shuttle B⁷, containing the continuous

weft, will be moved through the shed from either selvage or end of the loom and from the cell of the shuttle-box containing the same, whichever shuttle occupies its operative position at the level of the race of the lay 70 by picker-sticks B⁸, (one only shown,) that may be moved in any usual manner common to looms. Figs. 17 and 18 show one common form of devices for moving the picker-stick, and, referring to said figures, B⁶⁴ shows a 75 strap connected with an arm B⁶⁵ of a picker-actuating shaft B⁶⁶, sustained in bearings at the loom side and having a shoe B⁶⁷, that is struck by the roller B⁶⁸, carried by an arm B⁶⁹, fast on the shaft A¹⁰. The picker-stick, 80 Fig. 1, will cause the shuttle to traverse the warps and enter the usual box (not shown) at the opposite end of the loom-frame. The shuttle-box referred to has two stands B⁹ B¹⁰, that sustain a guide B¹², (shown as a rod, see 85 Figs. 1, 4, 5, and 6,) the guide being broken out partially in Fig. 4. This guide receives loosely upon it a carrier C, having a depending slotted arm C' and a projection C², (see Figs. 5, 6, and 7,) overlapping a portion of 90 the shuttle-box, said projection sustaining the weft-holder, comprising a stationary jaw a⁶ and a movable jaw a⁷, having a projection a⁸, that abuts the short weft held by the selecting means, said movable jaw being piv- 95 oted at a⁹ on the fixed jaw, the other end of said movable jaw having a cam projection a¹⁰. The movable jaw is acted upon by a spring a¹¹, that normally serves to close the jaws that they may grasp a selected short weft a, as 100 represented in Fig. 4, said weft having been selected from a mass of short wefts by nippers forming part of short-weft-selecting means to be described and held in the path of movement of the jaws of the weft-holder. The slide 105 C has a depending portion C', slotted as represented in Fig. 4, to be entered by a stud C³ of a lever C⁴, pivoted at its lower end on a stud C⁵. There is a slide and a lever C⁴ at each end of the loom, and that said levers may be actuated to 110 move said slides and weft-holders I have provided the cam-shaft A¹⁰ of the loom with a scroll-cam C⁶, the edge of which is made to travel between rollers b, revoluble about studs erected on a plate b⁷, that may tip on an arm 115 b' of a lever, the hub of which is erected on a stud b⁸, rising from a stand b⁹, connected with a suitable brace b¹⁰. The arm b¹¹ of the lever b' has a stud b¹², that receives the hubs of two like connecting-rods b¹³ b¹⁴ of different 120 lengths, each one, however, connected to a lever C⁴. As the scroll-cam is revolved once for each two motions of the crank-shaft, it will be noticed that, viewing Fig. 1, the slide C will be moved during a portion of the revolution of the shaft A¹⁰ and will then remain at rest for a portion of the revolution of said shaft and will then be returned to its starting 125 point, Fig. 1. The weft-holder may be opened sooner or later in the movement 130 .

thereof in the direction of the arrow 4, Fig. 5, by adjusting a weft-holder opener a^{12} , shown as a lever pivoted at a^{13} and made adjustable through an adjusting device a^{14} , shown as a screw held in a projection a^{14x} from the shuttle-box, the projection a^x of the movable jaw a^7 contacting with said weft-holder opener as the slide C is moved to the right from the position Figs. 1 and 5. The weft-holder when 5 the slide C² occupies its outward position (see Figs. 1 and 5) stands at a short distance to one side of the position of the short-weft-selecting means, to be described, that is to select and hold a short weft to be presented to 10 said weft-holder. When the slide C² is moved, as will be described, the projection a^x of the movable jaw of the weft-holder in the movement of the latter contacts with the first weft-holder opener a^{12} just as the jaws of 15 the weft-holder arrive at the point where the weft-selecting means holds a short weft a , (see Fig. 4,) that is to be given up to the weft-holder. The shuttle-box at its inner end sustains weft-holder-releasing means. (Shown 20 best in Figs. 6 and 6^a and at the right in Fig. 4.) The weft-holder-releasing means acts to open the weft-holder just as the latter starts to move outwardly from the position occupied by it, Fig. 6^a, while the short-weft-carrying shuttle traverses a shed, and, as herein 25 illustrated, said means comprises, essentially, a bracket a^{15} , connected with the shuttle-box or stand B¹⁰ and the mouth B^{5x} of the shuttle-box, said bracket having a stud-screw a^{16} , 30 upon which is pivoted an arm a^{17} , the outer end of which is shown as somewhat upturned (see Fig. 4) and offset (see Figs. 6 and 6^a) with relation to the part of the arm designated a^{17x} , the extremity of the upturned 35 portion of the arm a^{17} being somewhat rounded, as represented. The arm has a tail a^{18} , that is acted upon by a spring a^{19} , secured to the bracket a^{15} , said spring serving normally to keep the free end of said arm lifted, as 40 shown in Fig. 4, in line with the rounded projection a^x of the movable jaw a^7 . When the weft-holder is moved inwardly from the position Fig. 4 to the position Fig. 6^a, the projection a^x passes over and depresses the inner free end of the arm a^{17} , and the jaw is not 45 opened. The weft-holder opener having acted and the weft-holder having grasped a short weft, the weft-holder will be closed immediately by the spring a^{19} and holding the 50 short weft will continue its movement into the position Fig. 6^a, when the further movement of the slide will be stopped, and the weft-holder will hold the short weft at a short distance from the selvage of the fabric being 55 woven. During the movement of the weft-holder into this position the projection a^x met the inclined upper edge of the arm a^{17} and depressed said arm, the spring a^{19} yielding, and said holder was not opened. The 60 weft-holder is stopped with the projection a^x 65 of the movable jaw a^7 almost or substantially touching the rounded portion a^{2x} of the arm a^{17} . (See Fig. 6^a.) During the movement of the weft-holder, as described, the shuttle B⁶, provided with a series of short wefts, has 70 been or is being moved by the picker-stick referred to across the warps to its opposite box, and the selected weft, one portion of which is held by the weft-holder and the other portion of which is yet within the control of the shuttle, is paid out or trailed behind the shuttle as the latter crosses the warps and is deposited on the warps in the lower plane of the shed, said shuttle giving 75 up fully the short weft about as the shuttle enters the opposite box. The particular point at which the short-weft shuttle shall give up the short weft is not, however, of essential importance so long as said shuttle carries the portion of the short weft retained 80 by it, which weft has been selected and is held by the weft-holder and lays said weft across the warps of the shed. The short weft having been laid in the shed, the weft-holder must be opened to release the short 85 weft. This is done immediately as the weft-holder is started backwardly from its position Fig. 6^a into the position Fig. 6, the weft at this time being held by the closing shed. The weft-holder is started toward the left from 90 the position Fig. 6^a, and the projection a^x of the movable jaw contacts with the weft-holder-releasing means. As the short weft-holder is moved into the position Fig. 6 the projection a^x meets the rounded upheld end 95 of the arm a^{17} , said arm at this time, however, not yielding, and consequently the jaw a^7 is opened to release the short weft then laid and to be left in the fabric. It will be understood that the weft-holder will grasp the 100 short weft while yet held by the selecting means outside the shuttle, and while said weft is so held the shuttle B⁶ and the weft-holder will be started in their movement toward the right, viewing Fig. 4, the weft-holder being stopped next the selvage-warps and holding onto the short weft while the short-weft shuttle continues through the warp and delivers the selected short weft into the shed. It will also be understood that a 105 portion of each short-weft length will be left protruding beyond the selvage-warps at both sides of the fabric. 110

Weft-selecting means.—As shown best in Figs. 1, 2, 4, 7, and 8, the shuttle-box has 115 erected upon it a stand D of suitable shape to sustain short-weft-selecting means, said means, as herein shown, comprising a shaft D', sustained in suitable bearings of said stand, the stand having at its front end a 120 head D¹². The shaft D' has fixed upon it a nipper-opener cam D⁶, a stop-cam b²¹, and a belt-pulley E'. As the shaft rises and falls with the shuttle-box the shaft D' is shown as 125 being driven from a belt E, surrounding the 130

pulley E' thereon and deriving its movement from a pulley E'^x, carried by a shaft E³, having its bearings in an upright E⁴, connected with and rising from that portion of the 5 lay having the usual guideway in which the shuttle-boxes are moved up and down. The shaft E³ has a second pulley E², that receives a belt E⁵, surrounding a driving-pulley E⁶, fast on a shaft E⁷, sustained in suitable bearings 30 31 32 of the loom end. The shaft E⁷ derives its movement from a bevel-pinion E⁸, fast on the end of the crank-shaft, through a bevel-pinion 17^x on an upright shaft 18^x and bevel-pinions 33 and 34, said shaft E⁷ being 10 driven continuously as long as the crank-shaft is rotated. A crank-pin of the disk D⁹ enters a cam-groove in a block D⁹, fast upon a rod D¹⁰, having suitable bearings in the head D¹² and carrying at its lower end the 15 nippers of the short-weft-selecting means. These nippers, as herein represented, comprise a member D', connected by a screw a^{3x} with an enlargement at the lower end of said rod and a movable lever D², free to be turned 20 about a stud D³, carried by the member D' of the nipper. A spring 10 acts normally to close the nippers onto the short weft when the nippers are lowered in contact with the bunch of short wefts presented by the shuttle B⁸. The nippers have to be opened when 25 they approach the bunch of short wefts in order that they may grasp a short weft, and to do this I have provided a nipper-opener (shown as a lever D⁴) pivoted at D⁵, said 30 pivot being surrounded by a suitable spring 20^x, that normally acts to keep the short arm of said nipper-opener in contact with the nipper-opening cam D⁶. The stop-cam b²¹ on said shaft has a shoulder b²⁰, with which at 35 times coacts a stop-lever b¹⁹, mounted on a stud 39, carried by a projecting arm D^x of the framework D, the stop-lever when in the 40 position Fig. 7 arresting the rotation of the shaft D⁷ and retaining the weft-selecting nippers in closed position, holding a weft a, as 45 represented in Figs. 4 and 7. The nippers referred to and forming part of the short-weft-selecting means are and may be substantially such as represented in United States Patent 50 to Lindsley, No. 119,278, dated September 26, 1871; but the parts coacting therewith and herein illustrated are designed somewhat differently.

The head D¹² of the frame D has ears b¹², 55 that receive loosely a rod b¹⁰ of a stop-lever-moving device, comprising besides said rod a two-armed plate b¹⁴, (shown best in Figs. 4, 7, and 8,) the lower depending arm of which has a foot b¹⁵, adjustably connected thereto 60 by a screw b¹⁶. The rod b¹⁰ has at its upper end a nut b¹⁷, that limits the descent of said rod, and below its upper bearing said rod has a connected nut b¹⁸, against which bears the upper end of a spring b¹⁹. This spring (shown 65 in Figs. 4, 7, and 8, but omitted from Fig. 1,) is used chiefly as a counterbalance to overcome the weight of said rod and its attached parts and to aid somewhat in moving the stop-lever b¹⁹ from the position Fig. 8 into the position Fig. 7. The hub of the stop-lever b¹⁹ surrounds loosely the stud 39, and between the hub of said lever and the head 40^x of said stud there is interposed a spiral spring 40, that normally acts to hold said lever in the position Fig. 4. The stop-lever has a depending outturned portion 42, provided with a roller-stud 41. The end of the longer arm of the lever b¹⁹ is slotted to embrace a pin b²⁴, extended upwardly from the arm 12. 70

The stationary member D' of the nippers 80 has a projection provided with a groove leaving side walls 13, between which is mounted a slide-plate 14, having lugs 15, that receive and constitute bearings for the journals of a shaft 14^x, from which projects a short-weft feeler 85 16. The upper end of the shaft 14^x is surrounded by a spring 17, that acts normally to move the feeler into weft-feeling position, said feeler when moved by said spring traversing the position that should be occupied by the 90 short weft if engaged by the nippers, and in case a short weft is absent the feeler is arrested by the lower end of the plate 14 after, however, passing the lower end of the stationary member D'. The plate 14 is slotted, 95 as shown, to receive a pin projected from the nipper member D', to which pin is connected the lower end of a spiral spring 19, the upper end of which is connected with an extension of said plate, said spring acting normally to move said plate downwardly in said guideway until the upper end of the slot in said plate meets said pin, as shown in Fig. 7. The shaft of the feeler 14^x (see Figs. 4, 7, and 8) has a projection 18 and a downturned finger 100 20, said finger when the rod D¹⁰ occupies its lowest position meeting an incline 21 (see Figs. 4 and 8) on the top of the shuttle-box, said incline acting on said finger to turn the rod 14^x and move the feeler 16 away from 105 the lower end of plate 14 and outwardly with relation to the portion D' of the nippers. 110

The stop-cam b²¹ on shaft D⁷ has a shoulder b²⁰, (see Fig. 7,) that is engaged by the stop-lever, as shown, when the nipper is 115 raised and holds a short weft, the arm 12 of the two-armed plate b¹⁴ at such time moving said stop-lever from the position Fig. 8 into the position Fig. 7. The arm 12 turns the 120 stop-lever to arrest further movement of the shaft D⁷ only after the nippers have selected a short weft and holds it in position to be acted upon by the feeler preparatory to being engaged by the short-weft holder. In the descent of the rod D¹⁰ to put the nippers in 125 contact with the bunch of short wefts the lower end of the slide 14 meets a projection 14^x, connected, as shown, with the shuttle-binder 16^x, pivoted at 16², and said slide is arrested while the rod D¹⁰ continues to de- 130

scend, as in Fig. 8, and at this time the feeler 16 is turned backwardly by the incline 21 far enough against the spring 17 to permit the short weft, if selected, to be put in the path 5 of movement of said feeler.

Fig. 8 shows the nippers open and in position to be closed by the spring 10 when the nipper-opener D⁴ is permitted to move to the left in said figure by its spring 20^x, the cam 10 D⁶ being of such shape as to permit such movement. When the nippers are closed, the rod D¹⁰ is immediately lifted and the projection 20 of the feeler-shaft retires from the incline 21, letting spring 17 turn the feeler into 15 feeling position, and if the nippers have selected a short weft and hold the same in the path of movement of the weft-holder the feeler will meet the said short weft and the stop-lever will be turned to engage the stop-cam b²¹. 20 As the rod D¹⁰ is completing its upward movement after a short weft has been selected by the nippers the end of the projection 18 of the feeler-shaft, the feeler having met a selected short weft, is retained in such 25 position that it meets the foot b¹⁵ and lifts the rod b¹⁹, causing the arm 12 thereof to turn the stop-lever from the position Fig. 8 into the position Fig. 7, thus stopping temporarily the further rotation of the shaft D⁷ of the 30 short-weft-selecting means, and consequently the reciprocation of the rod D¹⁰ and nippers is stopped until at such time as the said rod and nippers in the cycle of operation of the loom should again descend to select another 35 short weft, when said stop-lever is moved, as will be described hereinafter, to release the stop-cam b²¹ and let the shaft D⁷ be again rotated. Should, however, the nippers fail to 40 catch a short weft, the feeler 16, when turned by spring 17 as the rod D¹⁰ is raised after an unsuccessful attempt to seize a short weft, will be arrested by the plate 14, which will leave the end of the projection 18 in such position with relation to the finger 15 of the 45 two-armed lever b¹⁴ that when the rod D¹⁰ and nippers rise the projection will not engage the lower end of the foot b¹⁵, and consequently the stop-lever will not be turned into position to stop temporarily the rotation of 50 the shaft D⁷ and suspend the operation of the short-weft-selecting means. In this way it will be understood that the nippers have one or more chances to engage a weft.

The action of the short - weft - selecting means takes place in a defined portion of the 55 cycle of operation of the loom, and at a pre-determined time with relation to the rotation of the crank-shaft, and if it should so happen that the nippers fail altogether to get hold of 60 a short weft in the period of time allotted for that action then of course other means than the stop-rod-moving means so far described must be provided for automatically moving the stop-lever from the position Fig. 8 into 65 the position Fig. 7 to stop the shaft D⁷ and

hold up the nippers in the position Fig. 7 until such time as the weft-selecting means should be again moved to select a short weft, the holding up of said nippers preventing injury to the same by the return of a shuttle 70 into its box. If the short - weft - selecting means fails to select and present a short weft, imperfect goods would of course be woven, and consequently for the production of perfect goods it is essential that the continued 75 movement of the shed-forming and shuttle-box-moving parts of the loom must depend upon the fact that the short-weft-selecting means has, within the time allotted for its operation, selected a weft. So, also, it will be 80 understood that in case a short weft should not be selected by the nippers of the short-weft-selecting means within the time allotted in each cycle of operation of the loom that the stop lever b¹⁹ must be moved independently of the rod b¹⁰ and its attached parts that said lever may be put into the position shown in Fig. 7 until the weft-selecting means is again to be started into operation. It will also be understood that the shaft D⁷ is held 90 temporarily at rest with the nippers of the selecting mechanism holding a short weft, as in Fig. 7, until that weft has been deposited properly in the shed and that thereafter in the proper position in the cycle of operation 95 of the loom the stop-lever b¹⁹ must be moved to release the cam b²¹ and permit the shaft D⁷ to be again rotated that the nippers may select another short weft.

The means for moving the stop-lever b¹⁹ 100 outside of the rod b¹⁰ and its connected parts, before referred to, will now be described, and it will be understood that the means to be described for this purpose is duplicated at both ends of the loom, so I need herein describe 105 specifically the parts at but one end of the loom.

The loom end (see Fig. 2) has a stud 47^x, on which is mounted a gear-wheel 47, that derives its motion of rotation from a gear 48, (see Fig. 1,) fast on the cam-shaft, said gear rotating twice while rotating the wheel 47 once. The wheel 47 has an attached cam 50, that in its rotation meets the foot 60 of a slide-rod 45, on the front end of which is connected 115 an arm 44. The slide-rod, surrounded by a spring 62 and having a fixed collar 61, is sustained in bearings of a frame 46, connected by screws 46^x to the end of the loom. The spring 62 acts normally to keep said foot in the path of movement of the cam 50, the lever 44 when the foot is out of contact with said cam being out of contact with the roller-stud 41. The cams 50 on the wheels 47 at 120 opposite ends of the loom are so located one with relation to the other that the action of each cam is timed to the requirements of the loom and to the operation of the short-weft-selecting means at opposite ends of the loom and to the movement of the short-weft shut- 125 130

tle. If in the operation of the short-weft-selecting means the nippers fail to select the short weft in the allotted time with relation to the cycle of operation of the loom, it will be understood that the rod b^{10} will not be lifted, and the shaft D^7 and short-weft-selecting means would continue to operate and the movements would be of no use whatever, so the stop-lever b^{10} must be moved at times from the position Fig. 8 into the position Fig. 7 by other means. When the nippers stand in the position Fig. 7, the foot b^{16} , carried by said rod, occupies its highest position and the extended arm 12 holds the stop-lever b^{10} , as shown in said figure, thus temporarily arresting the action of the weft-selecting means. In this situation in the continued movement of other parts of the loom the rotating cam 50, carried by the wheel 47, acts upon the foot 60 of the slide-rod 45 at exactly the proper predetermined time in the cycle of operations of the loom and moves outwardly the arm 44, fast on said rod, said arm contacting with the roller-stud 41, shown as carried by said stop-lever, thus sliding the hub of said lever on the pin 39 in opposition to the spring 40, this movement being for a distance sufficient to remove the upper end of said stop-lever from engagement with the projection at the face of the cam b^{21} , thus permitting the selecting means to be again started. As the cam 50 leaves the foot 60 spring 40 acts to move the stop-lever inwardly on the stud 39 toward the cam b^{21} into the position Figs. 4 and 8. From the position Fig. 8 said stop-lever may be moved into the position Fig. 7 by the following means: If, for instance, the nippers have selected a weft, the stop-lever b^{10} is put in the position Fig. 7 by the arm 12, before described, as it rises with the rod b^{10} , and as soon as the projection of cam b^{21} meets the end of stop-lever the selecting means is again temporarily arrested. If the selector fails to get a weft, the lay in its regular backward stroke causes the long arm of said stop-lever to be acted upon by the arm 44, extended from the rod 45, and turns said stop-lever about its stud 39 in a direction to put the upper end of said stop-lever in such position that it will meet the cam b^{21} , and as soon as the projection b^{20} of said cam meets the end of said stop-lever further rotation of the shaft D^7 , actuating the weft-selecting means, is stopped until such time as the short-weft-selecting means can be again permitted to act. When the shaft D^7 has been stopped, as described, to suspend the operation of the weft-selecting means after said means has failed to select a weft, the weft-selecting means must be again started in operation at a period when in the movement of the crank-shaft in the cycle of operation of the loom the time again arrives when the weft-selecting means should again operate. The weft-selecting means

can be started only by the action of the cam 50 on the foot 60 of rod 45, as above described.

Short-weft-controlling means.—To prevent any possibility of the short wefts left by the shuttle during its movement through the shed curling up or getting into such a position that when the reed meets the short weft to beat it into the shed said weft might be bent or looped, I have provided short-weft-controlling means that will act to retain said weft in the position in which it leaves the shuttle and hold the short weft until the reed meets and beats the same into the fell. This invention is not limited to the exact means shown for acting against and controlling the position of said short weft and preventing it curling in the shed; but I have herein chosen to illustrate for this purpose some or all of the warps, said warps being made to grasp the short weft by a preliminary partial closing of the warps onto the short weft immediately after or while the shuttle is laying said short weft in the shed and before closing and crossing the warps for a succeeding shed. The means for controlling the position of the short wefts by a preliminary closing of the warps, as stated, is shown in Figs. 11 and 12. The cam-shaft A^{10} has a cam G , that acts upon a roll G' of a forked leg G^2 , jointed at G^3 to one end of an elbow-lever G^4 , pivoted at G^5 . One arm of this elbow-lever has pivoted upon it at G^6 a rod G^7 , the upper end of which is adjustably connected with one arm of a lever G^8 , pivoted at G^9 and forked at its opposite end to embrace a stud G^{10} , extended from a hollow tube G^{12} , adapted to be slid in suitable guideways G^{13} , there being like tubes and guideways at the opposite ends of the loom. The hollow tubes G^{12} at their lower ends at opposite ends of the loom have connected with them in suitable manner—as, for instance, by set-screws—a cross-rod G^{15} , having, as shown, one or more connected fingers G^{16} , notched, it may be, at its lower end to embrace one or more warps. The lever G^8 has a stud d , that is connected by a link d' with a stud d^2 of a lever d^3 , slotted at its ends (see Fig. 11) to embrace a stud d^4 , extended laterally from a head d^5 , connected with the upper end of a rod d^6 , that in practice, as herein shown, is extended through the hollow rod G^{12} , said rod d^6 having suitably secured to it near its lower end a cross-bar d^7 , having one or more slotted fingers d^8 , like the fingers G^{16} . As shown, the fingers d^8 and G^{16} stand one in front of the other, and the prongs of the fingers at all times embrace some of the warp-threads, and when the fingers are separated to their farthest extent the slots between one and the next finger are of sufficient length to permit the shed to be fully opened by the shed-forming means, and when the fingers are closed, as shown in Figs. 11 and 12, then those warps embraced by the fingers are

brought together or have given to them a preliminary closing movement, so that they may act, as has been outlined, upon a short weft laid or being laid in the shed. Fig. 11 shows some of the harness-frames with usual heddles having warp-eyes to receive the warp-threads. These harness frames or heddles will and may be operated, as has been stated, in any usual manner according to the class of weaving to be done. The warps that are moved independently of the shed-forming mechanism to in this instance of my invention control the position of the short wefts and prevent them from curling are sustained by the whip-roll B', it having a slotted arm e', that is connected by link e with the lever G⁴, before referred to. Other warp-threads taken from the beam B are extended over the usual roller-rest B². The link and arm constitute part of an easing motion that permits slack in the warp-threads that are to be partially closed on and to prevent the short weft from curling up. In Fig. 11 the full lines f f in front of the reed represent the warps with the shed fully open, the shuttle shown by dotted lines in said figure being supposed to be moved through the shed while the lay is at its back center, as in said figure, and during this movement of the shuttle containing the short weft, one end of the weft being retained by the weft-holder, the short weft is laid in the shed by the movement of the short-weft shuttle through the shed, and supposing that the leading end of the short-weft shuttle has arrived substantially at its box at the opposite end of the loom and is about to give up the short weft then being laid by it, then at this time the controlling means coacting with said short weft acts to prevent any curling or wrong position thereof with relation to the length of the warps. At this time the cam G moves the hollow tubes G¹² and the rods d⁶ into the position Fig. 11 and immediately causes those warps, under the influence of the fingers G¹⁶ d⁸, to be moved toward each other, as represented by the inner threads marked f' in Fig. 11, and at the same time the whip-roll B' is permitted to descend to afford the necessary amount of slack to permit of such movement of the threads f' before the final action of the harnesses in changing the shed to enclose the short weft just laid therein, the warps so partially moved closing the shed sufficiently to enable said warp-threads to act as weft-controllers and keep the short weft substantially straight to be acted upon by the reed and be carried forward to the fell. In my invention as herein illustrated I have represented but a portion of the warps as used to control the short weft to prevent it from curling or getting out of place; but it will be understood that all of the warps might be so closed, if desired, by contact therewith of any suitable means without departing from my

invention—as, for instance, by the rods G¹⁵ and d⁷, the fingers G¹⁶ and d⁸ being wholly omitted, and these rods might be used by simply changing the shape of the cam G.

Shed-forming means.—The cam-shaft (see Fig. 3) has a cam H, provided with a groove that receives a roller-stud H', mounted on a lever H², connected by rod H³ with the lever A⁵ (see Fig. 13) for moving the knives 14 of the dobby-motion, such as indicated by like number in United States Patent No. 388,318, said knives engaging at the proper time hooks connected with harness-levers fully shown in said patent and joined with harness-frames having heddles, all as provided for in said patent.

Fig. 13 shows in position the worm-toothed gears h and h', secured, respectively, to the shafts h² h³, carrying, respectively, the shed-forming pattern chain or cylinder h⁴ and the shuttle-box pattern chain or cylinder h⁵, each designated by a dotted circle, as the same are and may be of conventional construction.

The shaft H⁷, sustained in suitable bearings H⁸, has worms H H' to engage and actuate intermittently said pattern-cylinders, said shaft having keyed to it near its inner end a clutch-hub H⁹, having an annular groove to receive a fork H¹⁰, which constitutes a clutch-mover. The clutch-hub H⁹ has a hole at its side next the toothed gear H¹², which is mounted loosely on shaft H⁷ and provided with a pin g (see Figs. 15 and 16) to enter a hole in the hub H⁹ whenever said pin registers with said hole. The gear H¹² is supposed to be driven constantly through a train of gearing (shown in Figs. 3 and 13) from a gear H²⁰ on the crank-shaft, the rotation of the gear H¹² being in unison with the motion of the crank-shaft. The fork H¹⁰ referred to is located at the end of an arm g', fast on an upright shaft g², suitably sustained in bearings 62 at the loom end, the lower end of said shaft having a second arm g³, that is extended forwardly to a point, as shown, under the breast-beam, where it is provided with a stud g⁴. A spring h¹⁰, surrounding shaft g², acts normally to cause the lever g' to move the hub H⁹ into its clutching position, Figs. 13 and 16. The stud g⁴ is adapted to be acted upon by a side cam g⁵, secured to a rock-shaft g⁶, usually employed to throw the shipper out of its holding-notch and stop the loom; but it will be understood herein that said shaft does not release a shipper and stop the entire loom. The shaft g⁸ will, however, be provided with its usual spiral spring to hold the side cam g⁵ normally in the position Fig. 3. This shaft is herein turned in one direction against said spring by the dagger g⁷, pivoted at g⁸ and connected by link g⁹ with an arm g¹⁰, carrying a feeler g¹², commonly used in connection with the usual weft stop-motion of the lay, said arm, when to turn said shaft, being lifted into the dotted-line position, Fig. 3, the feeler at such

time, owing to the absence of either the short weft or the continuous weft, having dropped into the dotted-line position, Fig. 3. When the dagger moves the rock-shaft g^6 , the cam 5 g^6 moves the lever g' to slide the clutch-hub H^6 longitudinally of the shaft from the position Figs. 13 and 16 into the position Fig. 15 in the absence of weft, immediately freeing the shaft H^7 from the control of gear H^{12} , 10 leaving said shaft and both pattern-cylinders at rest. The disconnection of the clutch-hub H^6 from the gear H^{12} is effected just before the pattern-cylinder is to be started to effect a change of pattern. The stopping 15 of the pattern-cylinders does not, however, stop the weft-selecting means, and the latter may continue to operate until stopped by the lever b^{10} , as before described, and the short-weft shuttle in the meantime continues to 20 move into position that the weft-selectors may engage a short weft, the movement being continued until a short weft has been selected. A weft having been selected and inserted, the feeler working with the lay will be 25 held up, and immediately the pattern-surface will be started, and this without a mispick. It will be understood when the pattern-surfaces are stopped, due to the absence of weft, that the knives 14 continue to hold 30 the same shed until such time as the short weft has been properly laid in the shed; also that the dagger g' , which engages and moves the rock-shaft g^6 through intermediate connectors, moves the clutch or pin which 35 stops the pattern-surfaces, just before a new weft is to be presented, to change the shed, and the knives 14 remain at rest until the pin again enters the clutch, which will occur when the selected weft is inserted in the shed. This 40 done, the feeler engages said weft and permits the dagger g' to pass under the rock-shaft g^6 . The action of spring h^{10} will cause the pin g' to enter when it registers with the hole in the hub H^6 , and the pattern-surface will then 45 be started immediately at the same place in its cycle of operation of the loom at which it was withdrawn, and at the same time the shuttle-box pattern-surface will be started.

In the operation of the loom as the lay is 50 going toward its front position to beat up the weft if a short weft is not in the shed the feeler g^{12} will fall into the dotted-line position before the cam H operates the knives for moving the usual harness-levers and also before 55 the shed-forming pattern-cylinder is turned to bring a new indicator in position to change the shed. When the dagger g^7 strikes the projection g^{8x} (see Fig. 13) of rock-shaft g^6 , the shaft g^2 is turned and 60 moves the clutch-hub H^6 to disengage the same from the driving-gear H^{12} , thus stopping the pattern-surface. The lay now is on its front center and starts to make one more revolution. The selector, as has been stated, 65 repeats its operation in the time allotted in

each cycle of operation of the loom until a short weft has been selected and is laid in the shed to sustain the feeler g^{12} , and the knives of the shed-forming mechanism are operated and remain in engagement with the same 70 hooked jacks, thus obviating changing the shed, this being made possible owing to the fact that the indicators of the arrested pattern-surfaces continue to act on the same hooked jacks. If a short weft is properly selected within the prescribed allotted time and laid in the shed, the dagger will pass under the projection g^{8x} of the rock-shaft g^6 without turning the same, and immediately 75 the spring h^{10} acts and allows the pin g' to enter the hole in the hub H^6 , starting the shaft H^7 and its worm to turn and move the pattern-cylinder, the latter being started before the cam H starts the movement of either 80 knife-bar from its extreme inward toward its extreme outward position.

The shaft H^7 is employed to actuate both the shed-forming pattern-surface and the shuttle-box pattern-surface. Each pattern-surface will have usual indicators and a 85 worm-toothed gear.

The arm g^3 has connected with it a chain h , carried over a sheave h' and connected with the pawl h^2 , employed for moving the ratchet-toothed gear h^5 for moving the take-up h^6 . 95 The movement of arm g^3 , as described, through said chain lifts said pawl from the teeth of said ratchet-toothed gear and stops further movement of the take-up.

In practice the crank-shaft will have applied to it usual fast and loose or a clutch pulley to control the movement of said shaft and the other shaft of the loom driven therefrom. If the supply of weft is exhausted, the crank-shaft must be stopped, and this 105 may be done by the operator or in any usual manner.

Having described my invention, what I claim, and desire to secure by Letters Patent, is—

1. In a loom, means to form sheds, a shuttle to carry a plurality of short wefts, and means to move said shuttle to leave a short weft in the shed.

2. In a loom, a shuttle adapted to carry 115 short lengths of weft, means to select said wefts singly, means to hold the selected weft, and means to move the shuttle to deliver therefrom a weft.

3. In a loom, a shuttle to contain a plurality of short wefts, weft-selecting means, and weft-holding means to engage and hold a selected weft, and means to move the shuttle while the weft-holder holds the weft.

4. In a loom, a shuttle-box, a shuttle to 125 contain a plurality of short wefts, means to select the wefts in said shuttle, and means to move the shuttle that it may deliver therefrom weft so selected.

5. In a loom, a shuttle-box, a shuttle to 130

- contain a plurality of short wefts, means to select a weft to be delivered from said shuttle, means to engage and hold the selected weft, and means to move the shuttle to deliver said weft.
6. In a loom, a shuttle - box, a shuttle adapted to receive weft doubled on itself, and selecting means to enter the shuttle between its ends and engage and select the weft.
7. In a loom, a shuttle - box, a shuttle adapted to receive a plurality of doubled short wefts, selecting means to enter the shuttle and engage one of said short wefts near its end, and withdraw said end from the mass of short weft in the shuttle.
8. In a loom, a shuttle - box, a shuttle adapted to receive a plurality of short wefts, selecting means to enter the shuttle and engage one of said short wefts near its end, and withdraw said end from the mass of short wefts in the shuttle, and means to exert tension on the mass of short wefts in the shuttle and the single weft being drawn therefrom.
9. In a loom, a shuttle-box, a shuttle to contain a plurality of short wefts, weft-selecting devices, means to actuate said devices to select a weft, and means to arrest further movement of said devices after selecting a weft.
10. In a loom, a shuttle-box having a connected guide, weft-selecting means sustained by said shuttle-box, short-weft-holding means comprising normally closed jaws, means to move said holding means on said guide, and means to open said jaws to embrace a selected weft.
11. In a loom, shed-forming means, a shuttle to carry a plurality of short wefts, and a shuttle to carry a continuous weft, shifting shuttle-boxes to contain said shuttles; means for selecting said short wefts and for moving said shuttles as desired through the shed.
12. In a loom, a shuttle-box having a connected guide, weft-selecting means sustained by said shuttle - box, short - weft - holding means comprising normally closed jaws, means to move said holding means on said guide, means to open said jaws to embrace a selected weft, and means to then open said jaws a second time that the short weft held by it may be discharged.
13. In a loom of the class described, a guide, a shuttle to contain short weft, selecting means to select a short weft to be delivered in the shed by the shuttle, a weft-holder comprising normally closed jaws, actuated means to slide said weft-holder on said guide to engage and deliver the weft, and means for opening said holder to release the weft.
14. In a loom, a shuttle to contain a plurality of short wefts, a shuttle or shuttles to contain a continuous weft, shed-forming mechanism, shifting shuttle - boxes, picking mechanism, short-weft-selecting means, a short-weft holder, a pattern - surface, and mechanism connected with the shuttle-boxes and controlled as to its time of movement by said pattern-surface to place the shuttle-box containing the short wefts and the selecting mechanism, or the shuttle - box containing the shuttle carrying the continuous weft in operative position with relation to the race of the lay, that the loom may weave a fabric having a series of short wefts and a series of picks of continuous weft, the number of picks of short weft and of continuous weft being controlled by said pattern-surface.
15. In a loom, a short-weft-carrying shuttle, means to select a short weft, means to move said shuttle through the shed, controlling means to act upon said weft in the shed, and prevent the same from curling or getting out of position therein before the action of the reed thereon.
16. In a loom, shed-forming mechanism, a short-weft-carrying shuttle, selecting means to select the wefts singly, means to move said shuttle to deliver a short weft, and oppositely-moving devices to contact with the warps in the upper and lower planes of the shed, and cause said warps to be closed onto so as to engage and produce tension on the short weft laid in the shed preparatory to crossing the warps for the next shed and beating the weft into the fell.
17. In a loom for weaving with short wefts, a short-weft-carrying shuttle, and short-weft-selecting means adapted to select a short weft from the bunch of short wefts in said shuttle, said selecting means retaining temporarily one end of said selected short weft, and a holder to which said weft-selecting means gives up the end of said short weft.
18. In a loom, a shuttle-box, a short-weft-carrying shuttle adapted to carry a bunch of short wefts, short-weft-selecting means co-acting with said short-weft-carrying shuttle, and occupying such position with relation to the shuttle-box as to enter the ends of the bunch of short wefts of said shuttle when the latter is in its shuttle-box.
19. In a loom for weaving with short weft, a shed-forming pattern-surface, means for selecting and laying the short wefts in the shed, a lay, a feeler to feel for a short weft laid in the shed, a device under the control of said feeler, and means intermediate said device and said pattern-surface whereby when a weft is absent from the shed said device will actuate said means and arrest the movement of the pattern-surface, the presence of weft in the shed rendering said device inoperative, thus permitting said means to be moved and effect the automatic starting of the pattern-surface.
20. In a loom, shed-forming mechanism, a pattern-surface, means for actuating said pattern-surface and shed-forming mechanism, means to lay weft in the shed, a lay, a feeler to feel for weft in the shed, and means inter-

mediate said feeler and said pattern-surface, whereby when a weft is absent said pattern will be stopped.

21. In a loom, shed-forming mechanism, a drop shuttle-box, a pattern-surface, means controlled by said pattern-surface to actuate the shed-forming mechanism, means also controlled by the pattern-surface to move the shuttle-box, a device coacting with the pattern-surface to move said pattern-surface or leave it at rest, weft-feeling mechanism, and means intermediate said feeler and device co-

acting with said pattern-surface to stop the pattern - surface when the weft fails, and means to effect the starting of the pattern- 15 surface when weft is supplied to the shed.

In testimony whereof I have signed my name to this specification in the presence of two subscribing witnesses.
